J. H. BEAN, OF MARIETTA, OHIO.*

Letters Patent No. 87,753, dated March 16, 1869.

IMPROVED HEEL-CUTTER.

The Schedule referred to in these Letters Patent and making part of the same.

To all whom it may concern:

Be it known that I, J. H. BEAN, of Marietta, in the county of Washington, and State of Ohio, have invented a new and useful Improvement in Heel-Cutters; and I do hereby declare that the following is a full and exact description of the same, reference being had to the accompanying drawings, and to the letters of reference marked thereon.

This invention relates to a mechanism for cutting out boot-heels, &c., and consists, mainly, in certain details of construction, which will be fully described hereinafter.

In the drawings—

Figure 1 is a side elevation of my invention;

Figure 2, an end elevation of the same; and

Figure 3, a detached perspective view of a portion of my invention.

To enable others skilled in the art to make and use my invention, I will proceed to describe its construction and operation.

A represents the bed-plate of the machine, which may be oval, square, elongated, or any suitable form, and is designed to be fastened to any desired surface by screws, *a*.

Near one end of the plate A is a circular recess, or countersink, in which is inserted the circular block B, of wood, with its upper surface flush, or nearly so, with that of the plate B.

b represents an upright or standard, which rises from the plate A, and is rigidly attached to the same.

This standard may be constructed with a curved arm, *b'*, as shown, or with one extending at a right angle from it.

C represents a second arm, directly below and in line with the arm *b'*.

Both arms, *b'* and *C*, have circular apertures, through which passes the vertical shaft *C'*, which is attached to the frame *D'*.

In connection with the shaft *C'*, and between arms *b'* and *C*, is a spiral spring, *c*, for the purpose of raising the cutter after it has been depressed.

The die-frame or holder *D'* is made in the form of a hollow square, on the under surface of two sides of which are bevelled flanges, *c' c'*, in which fit the correspondingly-bevelled edges of the die *D*, which is thereby rendered detachable at will, by simply raising a spring-bolt, *d*, which works in a projection, *d'*, on the outer end of the frame *C'*, the end of the sliding die having a corresponding projection, *d''*, in which is an aperture, which, when brought under the bolt *d*, the latter immediately springs into it and holds it fast. When the die is required to be withdrawn, it is necessary to raise the bolt *d*, which is provided with the head *d''* for that purpose.

The frame *C'* is also provided with the span or cross-piece *D'*, which is elevated sufficiently above the same to admit of the removal from above of the forms which

are cut out by the die, and also to provide suitable means for the attachment of the shaft *C'*.

To the upper end of the shaft *C'* is pivoted the swinging arm *E*, whose function is to remove the leather as it accumulates above the top of the frame *D'*. *e* is an arm, which projects at right angles from the arm *b'*, and is provided with an orifice, through which passes one end of a bent and weighted lever, *e'*, which is attached to a slide or catch, *F*, of the construction shown in fig. 3.

f represents a projection, on the arm *E*, which, when the shaft *C'* and arm *E* are depressed, slides down the plane inclined upper surface of the catch *F*, which, extending outward from the arm *b'*, throws the arm *E* out sufficiently far to clear the frame *D'*, and when the projection *f* passes the catch *F*, it falls inward, of its own weight, being assisted also by the spring *f'*, and the bent end *E'* striking the leather, which is forced upward by the die, throws it out, and thus prevents the same from clogging. In the mean time, when the shaft returns to its former position, the projection *f* engages with the bevelled under surface of the catch *F*, raising the same, until the projection passes above it, when the bent and weighted lever *e'* causes the catch to resume its position.

G represents a lever, which is pivoted at *g* to a vertical extension of the arm *b'*, whose function is to depress the shaft *C'*, with its attachments, which it accomplishes by means of the connecting-rod or treadle *H*, the lower extremity of which is provided with the ring or stirrup *h*, and which passes through a hole in the arm *b'*, the hole being somewhat enlarged to admit of the necessary play of the treadle.

i represents a washer, provided for the purpose of preventing the spiral spring *i* from slipping through the hole. Said spring is designed to keep the lever *G* in an elevated position.

J represents a vertical guide, which is attached to the upper end of the standard *b*, and adjustable by means of a screw-thread. The object of this guide is to regulate the play of the lever *G*, thereby restricting the depth of stroke of the die.

The operation of the machine will be readily understood.

When the treadle is depressed by its connection with the lever *G*, the shaft *C'* and its attachments are also depressed, as above described, with a sufficient degree of force to cut out the shape of the die in a piece of leather, at a single blow. On releasing the treadle, the die immediately rises, and is ready for another operation, which, when performed, pushes up the piece previously cut, which is thrown out by the bent arm *E*. It will thus be obvious that the mechanism is simple, effective, and not easily damaged, and is a production of great utility, the die being capable of a great variety of changes in form, as desired.

Having thus fully described my invention,

* Ass't to himself, Abraham Pratt & James A. Terney of the same place

What I claim, and desire to secure by Letters Patent of the United States, is—

1. The bent arm E, provided with the spring f', and having the projection f, in combination with the catch F and weighted lever e', arranged and operating substantially as and for the purpose described.
2. The die D, in combination with the bevelled frame C', when arranged as described, and held by the stop, for the purpose set forth.
3. In a heel-cutter, of substantially the described

construction, the tap-removing device E, f, F, and e', in combination with the cutting-device D D' D'', d d' d'', as described, for the purpose set forth.

This specification signed and witnessed, this 26th day of December, 1868.

J. H. BEAN.
